UNITED STATES PATENT OFFICE

FREDERICK H. KERNAN, OF IRVINGTON, CALIFORNIA

CONCRETE GUN

Application filed January 26, 1931. Serial No. 511,424.

This invention relates to pneumatic concrete placing apparatus or so-called "concrete guns", particularly as used in the lining of tunnels with concrete.

5 The principal object of my invention is to provide apparatus of this kind which will be more adaptable to tunnel work than prior apparatus of this kind, particularly in the feature of special construction whereby it is hung low to the floor of the tunnel so as to permit of direct loading with the charge from an ordinary portable, cylindrical tilting concrete mixer carried on a flat car rolled in on the same track on which the "gun" is supported and behind the same. Other features are the receiving end construction and traveling air jet operated from adjacent the charging end of the gun and which progressively ejects the material 10 from the nozzle at the forward end of the concrete container.

15 Further objects and features of construction will appear in the following specification and accompanying drawing.

20 In further detail the drawing shows, at Fig. 1 a side elevation of the concrete gun as in place on a tunnel track and with a cylindrical concrete mixer discharging its load into the rear end of the gun.

25 Fig. 2 is an enlarged side elevation, partly in section, showing the traveling air jet aperture, and adjacent parts.

30 Fig. 3 is a cross section of Fig. 2 taken along the line 3—3 thereof, and Fig. 4 is a plan view of the inner or revolving portion of the air nozzle showing the spiral air slit.

35 In further detail the apparatus comprises a concrete container formed of a horizontally disposed cylindrical portion 1 joined to an upwardly slanted portion 2 which may be cylindrical but is here shown as tapering to somewhat smaller diameter at its elevated end and where it is fitted with an airtight door in the form of a disk 3 pivotally mounted at 4 to swing inwardly and upwardly as indicated in the heavier dotted lines to a closed position as indicated in the lighter dotted lines. The pivot 4 of this door is a shaft passing through a suitable 40 stuffing box to the outside of the shell where

it is secured to the end of a lever 5 and which lever is pivoted at its outer end to the piston rod 6 of an air cylinder 7 pivotally supported at 8 to the side of the container shell, so that upon applying air pressure 45 through either hose lines 9 and 10 controlled by valve 11 on air supply pipe 12, the door may be opened or closed. It is of course evident that this door may be opened manually by means of lever 5 if desired. A 50 suitable gasket, not shown, is provided for making the door air-tight when closed.

The container is provided with four wheels 13 rollable on the tunnel car tracks 14, and the forward end of the cylindrical 55 portion 1 is provided with a funnel-shaped discharge spout 15 lying substantially flush with the bottom of the container and which spout terminates as a pipe 16 adapted for connection to the concrete conduit pipe 60 through which the concrete is ejected to position desired, such as in back of the lining forms for lining the tunnel.

65 The concrete is ejected by air pressure from a tubular nozzle 17 which extends air-tight through the upwardly slanted lower wall of rear section 2 of the container to lie along the bottom with its forward end terminating adjacent the spout 15, as dotted in Fig. 1.

70 This air nozzle is arranged with an inner revolving tubular piece 18 to which air is supplied under pressure from a pipe 19 and has a spiral slot 20 in its upper wall which may be revolved under a straight 75 slot 21 in the outer wall of the outer tubular portion 17 of the nozzle so as to effect a traveling air aperture as the inner portion is revolved. To provide for accurate manufacture and to take up wear the members 80 17 and 18 are tapered and a tubular liner 22 is interposed. This liner is provided with a straight slot 23 on top in register with straight slot 21 in outer tube 17.

85 Slot 21 is preferably slightly beveled outwardly as shown in Fig. 3 and covered with a piece of heavy wire screen 24 preferably welded in place along the edges, and spiral slot 20 terminates at both ends in a straight portion 20' 20'' so that a longer 90 95 100

full open slot may be had at each end of the spiral slot.

At the point of emergence of revolvable tube 18 from liner 22 is a stuffing box 25, 5 and at the outer end of tube 18 is secured a bevel gear 26 meshed by a pinion 27 secured to a shaft 28 carried along the under side of section 2 of the container and fitted at its upper end with a handwheel 29 for 10 manually turning spirally slotted member 18 of the air nozzle.

Extending axially rearward from the outer end 18' of member 18 is a rod 30 carrying a loose handwheel 31 which may 15 be grasped and bumped against a collar 32 fixed to the outer end of the rod, so as to loosen the long tapered nozzle sections in case they stick, or when desiring to remove them for cleaning or dressing.

20 The construction of the gun with its low-down body and upwardly slanted rear end was for the express purpose of end loading at the rear, and particularly from a tilting concrete mixer 33 as indicated in Fig. 1 25 wherein this mixer is carried on a wheeled truck 34 rolling on portable switch tracks 35 carried on flat cars as at 36 rolling along the central tunnel tracks 14.

30 The mixer 33 may be of any of the known types, power-driven or not, and with any desired form of power dumping mechanism, the toggles 37 being sufficiently indicative of such well-known construction.

35 By the arrangement shown it is possible to load the gun directly from the rear with a tilting concrete mixer or drum without conveyors of any kind as heretofore required, and besides this the design of the apparatus permits this to be done without requiring much head room, so that it is practicable in small tunnels.

40 In operation the container is filled to a point just below the lower edge of the door opening, the door is closed, air under pressure is turned into the nozzle 18 from hose 19 under control of a valve not shown, and the wheel 29 is revolved to first open section 20" of the slot. This will at once eject the concrete from the forward end of the 45 container through spout 15, and the attendant then slowly, or intermittently, turns the nozzle 18 to move the effective opening backward to successively pick off the concrete from the forward end of the charge until 50 it is all ejected. The slanted bottom of section 2 of the container constantly feeds the charge downward and forward to the air jet.

55 Air pressure of course at once builds up 60 in the whole container as soon as the advanced portion of the slot is opened to thus assist in the ejection of the mass from all points, so that the traveling aperture successively cuts off as it were the material 65 from the forward portion of the pile for

ejection by the force of the air from all sides.

It is manifest without further drawings that the spiral slot in the air nozzle need not be continuous, but that it could be a series of holes along a spiral path, and therefore the terms "slot" or "slotted" used herein and in the claims are intended to cover such an obvious variation.

Also it is to be understood that while my 75 apparatus is especially devised for the ejection of concrete, the word "concrete" is not to be taken as a limitation in this respect, as the apparatus may be used for ejecting other material. 80

Having thus described my invention what I claim is:—

1. Pneumatic ejecting apparatus comprising a receptacle having a substantially horizontally disposed cylindrical section joined to an upwardly slanted section, a spout adjacent the bottom and at the end of the cylindrical section, and a charging door at the elevated end of the slanted section. 85

2. Pneumatic ejecting apparatus comprising a receptacle having a substantially horizontally disposed cylindrical section joined to an upwardly slanted section, a spout adjacent the bottom and at the end of the cylindrical section, a charging door at the elevated end of the slanted section, means mounting said door for opening inwardly, and power-operated means for opening and closing said door. 90

3. In a pneumatic ejecting apparatus for concrete and the like, a receptacle provided with a discharge opening at one end, an elongated tubular air nozzle within the receptacle extending from a point adjacent said spout in a direction along the bottom of the receptacle, means for supplying fluid under pressure to said nozzle, said nozzle comprising inner and outer tubular members relatively rotatable, and one of the members being longitudinally slotted and the other spirally slotted whereby upon turning them relatively an air emitting aperture may be obtained at various points along said nozzle. 100

4. In a pneumatic ejecting apparatus for concrete and the like, a receptacle provided with a discharge opening at one end, an elongated tubular air nozzle within the receptacle extending from a point adjacent said spout in a direction along the bottom 105 of the receptacle, means for supplying fluid under pressure to said nozzle, said nozzle comprising inner and outer tubular members relatively rotatable, and one of the members being longitudinally slotted and the other spirally slotted whereby upon turning them relatively an air emitting aperture may be obtained at various points along said nozzle, and said spiral slot having straight end portions to coincide for a dis- 110

tance with the straight slot in the other member.

5. In a pneumatic ejecting apparatus for concrete and the like, a receptacle provided with a discharge opening at one end, an elongated tubular air nozzle within the receptacle extending from a point adjacent said spout in a direction along the bottom of the receptacle, means for supplying fluid under pressure to said nozzle, said nozzle comprising inner and outer tubular members relatively rotatable, and one of the members being longitudinally slotted and the other spirally slotted whereby upon 15 turning them relatively an air emitting aperture may be obtained at various points along said nozzle, and manually-operated means for revolving the members relatively.

6. In a pneumatic ejecting apparatus for concrete and the like, a receptacle provided with a discharge opening at one end, an elongated tubular air nozzle within the receptacle extending from a point adjacent said spout in a direction along the bottom 25 of the receptacle, means for supplying fluid under pressure to said nozzle, said nozzle comprising inner and outer tubular members relatively rotatable, and one of the members being longitudinally slotted and 30 the other spirally slotted whereby upon turning them relatively an air emitting aperture may be obtained at various points along said nozzle, a gear at the end of one of said members, a pinion meshing said gear, a shaft 35 to which said pinion is attached, and a hand-wheel at the end of said shaft for revolving said one of said members.

7. In a pneumatic concrete ejecting apparatus, a receptacle, an air ejecting nozzle 40 along the bottom of the receptacle comprising an elongated tubular member closed at one end and provided with means for escape of air for a distance along said member, a movable member within said tubular 45 member arranged for changing the effective position of the air escape along said tubular member.

8. In a pneumatic concrete ejecting apparatus, a receptacle, an air ejecting nozzle 50 along the bottom of the receptacle comprising an elongated tubular member and provided with a slot along its wall, an inner tubular member revolvably mounted within the first tubular member provided with a 55 spiral slot arranged to cross the slot in the outer member, means for supplying compressed air to the inner member, and means for turning the inner member.

9. In a pneumatic concrete ejecting apparatus, a receptacle, an air ejecting nozzle 60 along the bottom of the receptacle comprising an elongated tubular member and provided with a slot along its wall, an inner tubular member revolvably mounted within 65 the first tubular member provided with a

spiral slot arranged to cross the slot in the outer member and said spiral slot terminating at the end in a straight run to coincide with the slot in the outer member.

10. In a pneumatic concrete ejecting apparatus, a receptacle, an air ejecting nozzle along the bottom of the receptacle comprising an elongated tubular member and provided with a slot along its wall, an inner tubular member revolvably mounted within 70 the first tubular member provided with a spiral slot arranged to cross the slot in the outer member and said spiral slot terminating at the end in a straight run at both ends to coincide with the slot in the outer member. 75
